UNITED STATES PATENT OFFICE.

MILLARD VON HALLE, OF PALISADES PARK, NEW JERSEY, ASSIGNOR TO THE STANDARD CORSET COMPANY, OF NEW YORK, N. Y., A CORPORATION OF MASSACHUSETTS.

CORSET.

Application filed June 19, 1922. Serial No. 569,343.

To all whom it may concern:

Be it known that I, MILLARD VON HALLE, a citizen of the United States, and a resident of Palisades Park, in the county of 5 Bergen and State of New Jersey, have invented certain new and useful Improvements in Corsets, of which the following is a specification.

My invention relates to improvements in 10 corsets and particularly to that type of stays commonly known as a reducing corset. Its main object is to provide a corset that will, in addition to the usual functions of such an article of apparel, serve as an abdominal support and reducer.

The invention is embodied in one concrete and preferred form in the accompanying drawing, which shows a plan view of the 20 body parts of a corset fastened or hooked together at the front but with the back of the corset unlaced or open.

1 indicates the usual body parts of a back-laced corset having vertical inserts of resilient material 2 that are common to corsets 25 of this type. 3 are the usual hook-end-stud fasteners for closing the front of the corset attached in the usual manner to the front steels, bone, or other stiffening material 4 of the corset. 5 indicates the two supporting and reducing parts which are here permanently secured at one side or edge 6 to the 30 corset, one on each side of the front steel or bone 4.

The parts 5 each comprise two strips of 35 resilient material 7^a and 7^b arranged in oblique relation to each other so that they overlap and so that a straight substantially vertical edge is formed on each side of the supporting and reducing part 5, as at 40 6 and 8, the edge 6 being of greatest length and the overlapping of the strips being of least extent at that side of the supporting and reducing part 5 that is permanently secured to the corset. The extent of the overlapping of the strips 7^a and 7^b increases toward 45 the free end of the support until at the outer edge 8 of the support 5 they are almost completely overlapped where they are securely fastened or joined together so as to form a strong support for one end of an adjusting means 9 attached to said straight edge midway between the top and bottom thereof to exert a pull upon the supporting and reducing means. The other end of the 50 adjusting means 9 is permanently secured

to the corset at some point distant from and substantially in the same horizontal plane as the point of attachment of the first mentioned end. Any of the well known adjusting means may be used for this purpose, that here shown being the usual strap and buckle arrangement comprising a loop 10, for holding a buckle 11 and a strap 12 for engaging with the buckle for pulling and adjusting the part 5 into proper position on the form of the wearer of the corset.

After the corset has been, in the usual manner, placed in position on the body of the wearer, a pull upon the strap 12 of the adjusting means will exert a pull or strain 60 upon the supporting and reducing part 5 that, because of the oblique and overlapped arrangement of the parts, will tend by means of the lower edge of strip 7^b to lift and, after the adjusting means has been fastened 65 to sustain this pull or strain, to hold in elevated position any superfluous flesh at the lower part of the abdomen of the wearer and by means of the overlapping of the strips 7^a and 7^b to flatten circumferentially 70 such superfluous flesh thus distributing it more evenly over that part of the body of the wearer and thereby improving the appearance, the lower edge of strips 7^b and the upper edge of strip 7^a holding such 75 superfluous flesh in position.

The strips 7^a and 7^b being of resilient material any undue pressure that would detract from the comfort of the wearer is avoided and the overlapping of the strips 7^a and 7^b afford the desired degree of strength 80 at the point where the greatest reduction or flattening is required.

A reinforcing strip of any suitable material may be applied to the outer edge 8 85 of the part 5 if desired.

I claim:

1. A corset comprising the usual body parts having suitable means for lacing and fastening these parts together around the 100 body of the wearer and having permanently secured thereto, at a suitable point below the waist line of the corset, means for supporting and reducing the abdomen of the wearer comprising: two parts, one of which is located on one side of the front opening of the corset and the other of which is located directly opposite on the other side of the front opening of the corset, each of these parts consisting of two strips of resilient 105 110

- material and each of the two strips being permanently secured at one end to the corset in oblique relation to the front opening thereof and in oblique and overlapped relation to each other, so that as they recede from said front opening the extent of the overlap is increased, the free ends of these two strips being fastened together to form a straight vertical edge, and an adjusting means secured to said straight edge midway between its top and bottom edges and also at a point in the same horizontal plane to that part of the corset to which said supporting and reducing means is permanently secured.
2. A corset comprising the usual body parts having suitable means for lacing and fastening these parts together around the body of the wearer and having permanently secured thereto, at a suitable point below the waist line of the corset, means for supporting and reducing the abdomen of the wearer comprising: two parts, one of which is located on one side of the front opening of the corset and the other of which is located directly opposite on the other side of the front opening of the corset, each of these parts consisting of two strips of resilient material and each of the two strips being permanently secured at one end to the corset in oblique relation to the front opening thereof and in oblique and overlapped relation to each other, so that as they recede from said front opening the extent of the overlap is increased, the free ends of these two strips being fastened together to form a straight vertical edge and an adjusting means for exerting and sustaining a pull upon said supporting and reducing means to lift by means of the lower oblique edge of the support any superfluous flesh at that part of the body of the wearer and to hold such flesh by means of the oblique top and bottom edges of the support in position and to flatten such superfluous flesh circumferentially by means of the overlapped strips, said adjusting means being secured in the same horizontal plane to the straight vertical edge of said supporting and reducing means midway between the top and bottom edges of said vertical edge and to that part of the corset to which said supporting and reducing means is permanently secured.

Signed at New York city, in the county of New York and State of New York, this 5th day of June, 1922.

MILLARD VON HALLE.
